United States Patent Office.

JOHN BULLARD, OF HYDE PARK, VERMONT.

Letters Patent No. 99,398, dated February 1, 1870.

IMPROVEMENT IN MITRE-BOX.

The Schedule referred to in these Letters Patent and making part of the same.

To all whom it may concern:

Be it known that I, JOHN BULLARD, of Hyde Park, in the county of Lamoille, and State of Vermont, have invented a new and useful Improvement in Mitre-Boxes; and I do hereby declare the following to be a full, clear, and exact description thereof, sufficient to enable others skilled in the art to which my invention appertains, to make and use the same, reference being had to the accompanying drawing, forming part of this specification, and in which—

Figure 1 is a top view of a mitre-box provided with my improvements, and

Figure 2 is a side elevation of the same.

This invention consists in the improved construction of the mitre-box, as hereinafter set forth, and in the provision of a slide, having spring stops, a set-screw to be used in cutting "spring" mouldings, and adjustable gauges fitted to the saw-frames, to facilitate the cutting of tenons.

I will now proceed to give a detail description of my invention, referring to the drawings, wherein similar letters of reference indicate like parts in the two figures.

A represents the bed or bottom of the mitre-box, and

B B, the sides thereof, having saw-channels *a a*, at the outer ends of which are placed vertical frames C C, provided with grooves in their inner faces to receive the sliding saw-gates D. These gates are made of wood or metal, with large openings c, to receive the back of the saw, and open slots d, for the passage of the saw-blade.

The gates D must be of such length that when a narrow saw is used, it will be so supported that its cutting-edge will but just touch the bottom of the box without injuring the same. If the gates are non-adjustable, only one width of saw can be used, and even this cannot be employed after the back of the saw has become narrower, and the openings which receive it are elongated by wear, unless (which may be the case) the sharpening of the saw will tend to narrow the blade to such an extent as to compensate for the wear of the back, and the elongation of the openings c.

To provide for the wear of the saw and gates, and for the use of saws of different widths, at any time, I make the gates vertically adjustable in their frames, by fitting a set-screw, e, in the bottom of each slide.

Instead of adjustment by means of set-screws, a slide, f, which may be graduated, can be fitted to each gate, by means of a screw passing through a slot. By setting this slide, (its lower end projecting below the gate,) the gate can be adjusted as desired. The mode of adjustment first described is, however, preferable.

These slides f have also another office. When it is desired, (in cutting tenons, for instance,) to cut only to a certain depth, the gauges or slides f are properly

set, so that their lower ends resting either on the wood to be sawed or the bottom of the box, the saw is prevented from cutting below the point desired.

It is often necessary in carpentry and cabinet-work to cut mitres at angles, varying but slightly from those for which provision is made in the box, and this requires the exercise of much care, with vexatious calculation and loss of time. In the present invention provision is made for cutting these slightly-varying angles.

The vertical frames, in which the saw-gates are fitted, are attached to the sides of the box by means of screws i i i, which pass either through slots or enlarged screw-holes; and g g are screws swivelled to the sides of the said frames, and working into the sides of the box. These screws have square portions to which a suitable wrench may be fitted, to turn the screw and thus adjust the frames, and with them, the said gates, laterally. By such adjustments, angles like that shown by dotted lines, fig. 1, can be cut.

E represents a slide, which is fitted in a groove in the bed of the mitre-box, and extending from end to end of the latter. This slide is marked with a scale of inches and fractions throughout its length, or, at least, for a short distance at one or both ends. Near each end of the slide is a slot, in which is fixed a spring-hook or stop, x, so made as to keep the work which is being cut from moving. The hooks are so made as to be depressed when the work is laid on their top. A notch may be made in the slide, as at h, to facilitate its adjustment.

To use this slide, it is adjusted to the desired position and there fixed by turning the set-screw j, which, at its inner end, bears against the slide. The moulding or other strip is then placed in the box, with its end against the stop. This slide is especially useful when it is desired to cut several pieces of work to the same size, for it is only necessary to set the slide once. Without this slide, it would be necessary to use the square and scratch-awl for each cut.

F is a long set-screw working through the side of the mitre-box, and having a head on its outer end for convenience in turning the screw. This screw is used in cutting spring-mouldings, which are set on edge in the box, in a position more or less oblique, according to the adjustment of the screw, which presses against the side of the moulding. Thus, by regulating the screw, the moulding may be cut at almost any desired angle. This screw F can also be used for holding any moulding while it is being cut, by adjusting the screw so as to exert lateral pressure on the strip or moulding, and thereby bind it in place.

G is a block, made adjustable in a slot, k, in the bottom of the box, and fixed by means of a set-screw, l. This block serves as an extension of the side of the box, which is very useful in cutting spring-mould-

ings, and also when using the saw in the end-gates shown at the left in the drawings, as it provides a firm support for the moulding or strip being cut, especially if the moulding or strip be very short.

H is a wooden block, pivoted centrally to the under side of the box, and having the projections m m, which, coming in contact with the sides of the bed A, limit the movement of the part H, and render it steady. n is a pointed projection, (of which only one side is shown,) on the bottom of the box, which also assists in keeping the block steady when it is adjusted. A plate, o, is set in the bottom of the box, below its upper surface, and having a curved slot. p is a set-screw passing through the slot into the block H. It will be seen that by means of this screw, the part H can be fixed at any point within the limits of its movement. q is a pointer on the piece H, which indicates on a graduated surface, r, the angle at which the said part H is fixed, and thus assists in setting the latter at any desired angle. s s are saw-gate frames, similar to the others, pivoted, one at each end of the piece H, by means of set-screws t, passing through a slot, u. By this means the frames s s can be adjusted laterally, at either side, to an angle of forty-five degrees or less, the piece H remaining in the position shown; or, as the nature of the cut to be made may require, the part H and the frames s s may both be independently adjusted. This device will enable one to cut at any angle commonly required, as many adjustments may be

obtained by this arrangement not possible with the other saw-gates and frames.

To the under side of the box are attached cross-pieces v v, having screws or pointed pins projecting downward at their outer ends, so as to penetrate the surface on which the mitre-box is usually placed, and thereby keep it from moving about while being used.

The mode of using this box, after the several parts have been adjusted as before described, is the same as with all mitre-boxes, and therefore requires no further description.

The advantages of my improvements will be readily seen from the above specification by those interested in and acquainted with the use of mitre-boxes.

Having thus described my invention,

What I claim as new, and desire to secure by Letters Patent, is—

In the mitre-box herein described, the arrangement of the gates D D, frames O, screws g g, slide E, gauges f f, applied to the gates D, set-screw F, block G, frames s s, and cross-piece H, all constructed and arranged in the manner specified.

To the above specification of my invention, I have signed my name, this 13th day of September, 1869, in the presence of two subscribing witnesses.

JOHN BULLARD.
